UNITED STATES PATENT OFFICE.

PERRY L. HEDRICK, OF EL CENTRO, CALIFORNIA.

SIPHON FLUME-GATE.

1,284,671.

Specification of Letters Patent. Patented Nov. 12, 1918.

Application filed January 30, 1917. Serial No. 145,528.

To all whom it may concern:

Be it known that I, PERRY L. HEDRICK, a citizen of the United States, residing at El Centro, in the county of Imperial and State 5 of California, have invented new and useful Improvements in Siphon Flume-Gates, of which the following is a specification.

This invention relates to pneumatically operated flume gates, and the principal object is to provide a flume gate which is operated without the use of valves or valve seats.

It is also an object to provide a flume gate in which the passage of water therethrough is controlled by means of an air seal.

15 It is an object to provide a siphon that will operate continuously and one in which the air from the water will not collect at its top and break or stop the siphonage.

The invention further has for its object to 20 provide a flume gate for irrigation and hydraulic purposes which will be simple, strong, durable, economical in its construction and which in its usage will be a safeguard against leakage and floods.

25 Another object of this invention is to provide a gate that will automatically prevent the water from overflowing the canal bank.

Another object of this invention is to provide 30 a pneumatically operated flume gate having an entrance opening normally above the water level in a canal or flume, and a discharge opening below the normal level of said water exterior to the canal levee or 35 wall of flume.

It is also an object of this invention to provide 40 a flume gate of tubular construction, the end of the tubular structure projecting above the water in a canal, being provided with a hood or cover in which air can be confined or relieved as desired.

It is also an object of this invention to provide means to regulate the flow of fluid through the entrance opening of the gate by 45 means of an adjustable hood or cover.

It is also an object to provide means in connection with the hood or cover to permit of submergence of the entrance opening without leakage and also to permit of over- 50 flow of the excess water in the flume so that there is no danger of overflow in the latter, together with means for operating covers of large size in relation to other portions of the gate.

55 It is also an object to provide pneumatic means for controlling the flow into and in

excluding it from large sized gates in submergence without shifting the cover from a fixed position.

It is a further object to provide means for 60 reversing the position of the gate so that it may be operated from the land side of the flume and gate.

With the foregoing and other objects which will appear as the description proceeds, my invention consists in the construction, combination and arrangement of parts hereinafter described and claimed.

In the accompanying drawings which form a part of this specification I have illustrated a convenient and practical embodiment of my invention and in which:

Figure 1 is a transverse section through one embankment or levee of a flume or canal showing the gate in section, the hood or 75 cover being in position ready for operation.

Fig. 2 is a similar view showing a portion of the tube in elevation, the operative position of the gate hood or cover being indicated, the flow of water within the tube 80 having been started by means of the cap.

Fig. 3 is a perspective view of the protective collar encircling the standpipe.

Fig. 4 is a side elevation of protective 85 collar.

Fig. 5 is a transverse section of a modification or reversal of the construction in which the cap is operated from the land side of the levee.

Fig. 6 is a separate view in elevation of 90 the hood or cover with sliding cover supports in place.

Fig. 7 is a plan of one of the cover supports.

Fig. 8 is a detail section of a cover operating under a variable head of water, and section of a device for lifting large sized covers.

Fig. 9 is a transverse section on line A—B 95 Fig. 8 showing the concentric relation of the walls of the tube and the hood or cover.

Fig. 10 is a perspective view of the outlet end of the tube.

Fig. 11 is an end elevation of plug in end 100 of tube 17.

Fig. 12 is a side elevation of an operating lever for lifting the siphon cover.

Heretofore in the operation of flume or canal gates the valves and seats have become worn and leaky and on account of their connection with a flume or canal are difficult 110 of inspection and repair unless the supply is

turned off at some distant point in the system resulting not only in considerable waste of water and time, but no means is made to provide against overflows and levee protection.

This invention overcomes the above difficulties in providing a construction without valve seats or contacting parts in which the flow of water is controlled by air, a siphoning action being produced by shifting the portion of the air in relation to a fixed portion of the gate.

More specifically in the drawings, 14 represents or designates a levee or embankment forming one side of a canal having water 15 therein, it being desired to convey this water to the land level 16. To accomplish this the pipe 17 is placed in the levee at any suitable point either in the inclined position shown 20 having the end disposed practically on a level with the ground 16, or placed so that the pipe is trapped in its course from the inlet to the outlet, and jointed at its opposite end 19 with a standpipe 20 which preferably extends above the level of the water 15 but which with extremely variable heads of water may be submerged when the water reaches height 15 Fig. 8.

It has been found in practice that this 30 pipe 17 should be made of cement but it may be built of metal or wood, the stand pipe 20 may be either of cement or metal structure, the latter being substantially vertically disposed with the opening or inlet in a plane 35 parallel to the water surface.

The hood or cover 21 encircling standpipe 20 is preferably a tubular or cylindrical structure having its tubular walls extending downward preferably at right angles to its 40 closed end 22 and of such length as to extend some distance below the level of the water and prior to use may be left resting upon the upper end of stand pipe 20.

To operate this cover a handle 23 is secured to the top thereof and suffices for small sizes, for large sized covers where no submergence occurs hooks 24 are secured to the sides of the cover into which rings of a crossbar 60 may be engaged, the crossbar being 50 attached to a simple lever 25 with fulcrum 61, when in use resting upon collar 26.

To regulate the flow through the stand pipe 20 and pipe 17 means are provided to support cover 21 in a raised position by a 55 strap frame 27 provided with latch 28, this frame being free to slide in grooves formed by straps 24 and 29 the latch engaging in cross slots cut into 29 and prevent the descent of the cover 21 when in raised position thus holding the closed end of cover 60 out of contact with the top of standpipe 20, these holding devices bear down upon opposite sides of collar 26.

In the modification shown in Fig. 5 the 65 outlet pipe 30 is reversed, its upper end be-

ing located in the canal in the water 15, the opposite end connecting to stand pipe 31 which extends beyond the land side of the levee 14, the standpipe 31 is vertically disposed and is provided with a cover 32 similar in form to cover 21 the end of the standpipe extending above the level of the water 15 as in the first instance.

To provide a seal for the cover 32 a receptacle 33 is provided, which encircles the standpipe and is of sufficient diameter to inclose the walls of the cover 32 and of sufficient height to allow the cover to be raised sufficiently to start the flow or siphonage of the water without breaking the air seal. 80

To provide means for admitting water to form this seal a small auxiliary valve 34 is tapped into the standpipe so that water standing within the standpipe at the same level as in the canal can be readily withdrawn into the tank 33 for the purpose desired.

For filling the trap in the pipe 17 priming valve 35 is mounted in stand pipe 20 by means of which water 15 may be admitted to 90 fill trap to ground level 16.

In the modification or application shown in Fig. 8 adapted to be used where submergence occurs and where covers attain such size and weight that it is difficult to 95 operate them manually without mechanical devices, the cover 36 over the standpipe 20 is provided with a cable support 37 which leads to a block 38 of the block and tackle, the line 39 being carried to any suitable 100 point, this tackle being supported upon the arm 40 of a bracket 41. This bracket 41 consists preferably of a suitably formed rod or post of iron or metal having a seat upon the floor 42 of the long leg of the siphon 105 17 and passing up through and being concentrically located with the walls of the standpipe. To accommodate this post the cover 36 has an orifice through its top 43 through which is secured the pipe 44 this 110 latter being concentrically arranged with the side walls of the cover and embraces the post 41, and besides providing means for accommodating the post 41 also permits of overflow in case the water level of the canal attains a height which would be dangerous 115 to the continuity of the levee.

The cover 36 is provided with a false tight horizontal wall 50 but is extended to join with the top 43 allowing of submergence of 120 the stand pipe 20.

To provide for conditions where the water level rises to greater height than the top of the standpipe 20 Fig. 8 and would tend to lift the cover by buoyancy and start siphoning action by reason of overcoming the weight of the cover by the confined air within the same being put under greater compression by the rising water 15, the post 41 is provided with a bore within which a pin 130

46 is introduced which forms a stop to limit the upward movement of the cover.

To provide for conditions of operation when the water level rises to 47, an air valve 48 is provided mounted in the top of cover 43 and connected by pipe 51 through false cover 50, air valve 48 forms a means for releasing air under compression within cover 36 and also forms means for air hose connection for introducing air under compression to stop water flow under cover 36 and standpipe 20.

To provide for the delivery of water in straight lines and to prevent whirls at the delivery 16 and to prevent levee erosion at the outlet the upper portion of 17 equal to the cross sectional area of 17 is cut away at 18 Fig. 1, at the end of the lower portion of pipe 17 which is not cut away is fitted a plug 52 Fig. 10 and Fig. 11. This plug is preferably placed at right angles to the axis of pipe 17 and has its central portion 53 formed to a higher level or low peak than at the sides where it joins with the sides of the pipe. The higher central portion by adding obstruction and additional frictional resistance checks the films of highest velocity and renders an equal velocity to all parts of the flow.

The operation of the gate will now be explained, water is admitted through auxiliary valve 35 Fig. 1 until it stands in the long leg of the siphon and standpipe to the height shown, the cover with air valve 54 open is now lowered over the standpipe until the top 22 rests upon the top of standpipe, the water now stands within the cover and surrounds the standpipe to the height shown, by closing the air valve the cover becomes airtight and then by lifting the cover to the level shown in Fig. 2 the tendency is to create a vacuum under the cover, by thus lessening the air pressure upon the top of the water surface both within the standpipe and within the cover surrounding the standpipe allows the full atmospheric pressure to be exerted downward upon the water surface external to the cover in the canal and upon the water in the trap at the landward end of the pipe at its opening 18 and thus force the water upward within the standpipe and within the cover, these water surfaces will be carried upward by the ascending cover at its rate and will maintain their same relative elevations with respect to each other that they had prior to raising the cover, when the cover has been raised a distance equal to the height of the standpipe above the water in the canal, the annular column of water then at this point becomes unsupported and falls within the standpipe while the atmospheric pressure upon the outside of the cover forces other water in to take its place, the water falling within the standpipe will entrap any air within the cover and

carry it out of the long leg, thus maintaining a siphon, continuously, through the cap, standpipe and long leg to deliver water to the land 16 clearly as shown in Fig. 2.

The operation of the structure shown in Fig. 5 is the same as disclosed in Fig. 1 and Fig. 2 it being merely reversed in that the water stands in the standpipe 56 at the same height as in the canal, and water admitted into the basin 33 through auxiliary valve 34 forms a seal for the cover 28 and on lifting the same, water in the standpipe is lifted until it overflows and starts a flow through the siphon, standpipe and receptacle upon the land.

Where the head of the water is variable as in Fig. 8 siphonage from water level 15 is obtained as previously described but a flow from 47 is obtained by opening valve 48 and releasing the compressed air from under the cover 36 which allows the water to flow directly from a higher to a lower level.

To stop the flow of water compressed air is introduced under the cover preferably through air valve 48 from some previously provided supply.

By means of this invention water may be lifted and discharged into a standpipe at a height above the normal water level equal to the maximum height of a water column sustained by the atmospheric pressure.

The amount of flow is regulated by shifting the position of the cover vertically and increasing or decreasing the space between the top of the cover and the upper end of the standpipe. To stop the action, the valve 54 may be left entirely open admitting air under the cover and breaking the siphoning action, or it may be stopped by removing the cover from the standpipe. The open standpipe is then a levee protection.

I claim:

1. In a siphon flume gate construction in combination with a levee forming one wall or embankment of a canal having water therein, of a standpipe vertically disposed in said canal adjacent said levee or embankment having its upper end open and extending above the normal level of water in said canal, the lower end of said standpipe being connected to a pipe carried through said embankment or levee and opening upon the land side thereof at a lower level than the upper end of said standpipe, a cover embracing said standpipe and extending above and below said water level in said canal whereby when said cover is lifted the water level therein is raised above the top edge of said standpipe, means to support said cover in its lifted position.

2. In a siphon flume gate construction in combination with a levee forming one side of a canal having water therein of a standpipe vertically disposed in said canal and having its upper end adjacent to or above

the water level in said canal, an elbow of angular configuration connected to said standpipe below the level of said water, a pipe extending from and connecting with 5 said elbow to a point on the oppositely disposed side of said levee and having its opening adjacent the land level thereto, said opening being below the water level in said canal said opening being in the upper wall 10 of said pipe, means provided in the landward end of said pipe to divert the water upward through said opening, a tubular cover having a closed upper end, said cover adapted to embrace said standpipe and extend 15 into the water adjacent thereto, means to release or receive air in the upper portion of said cover, and means to lift said cover so that the level of the water will be varied within said cover to a point above the 20 top edge of the standpipe and start a siphonage flow from the water in said canal to the land side of the levee through said cover, standpipe and pipe connections thereto.

3. In a siphon flume gate construction in 25 combination with a levee forming one wall of a canal having water therein, of a stand pipe vertically disposed in said water and supported adjacent said levee, having an open top adjacent to the water level in said 30 canal, a connection extending from the lower end of said standpipe to the oppositely disposed side of said levee to form an exit for water therefrom, a cover support mounted in said standpipe and extending 35 above the top thereof, means to raise or lower a cover secured to the upper end of said cover support or post, a cover having a concentrically arranged tube therein, said cover adapted to embrace said rod and in- 40 close said standpipe, and means to connect said cover to said cover raising means, whereby said cover may be raised or lowered in relation to said standpipe to produce a

siphoning action and deliver water through said cover standpipe and tube from said canal to the land side of said levee. 45

4. In a siphon flume gate construction in combination with a levee forming one side of a canal of a standpipe mounted adjacent thereto and affording communication with the water inclosed by said embankment, a cover adapted to close the upper end of said stand pipe, and a stationary collar or sleeve arranged in spaced relation with the cover to provide a water seal for said cover so that variations in the level of the water confined in said cover and said stand pipe may be produced to start a flow from said canal to the land side of said levee or embankment. 55

5. In a siphon flume gate construction in combination with a levee forming one side of a canal having water therein a standpipe mounted adjacent thereto having an open top below the water level of said canal, a connection extending from the lower end of 60 said stand pipe to the oppositely disposed side of said levee to form a trapped passage way exit for water from said canal through said stand pipe and its connection to the land side of said levee, a cover having a closed upper end, said cover adapted to inclose said stand pipe, means to fix said cover in position inclosing said stand pipe, means provided in said cover to admit of air passage between the underside of said cover 70 and the exterior, means for preventing water flowing under said cover and through said stand pipe and its connection to the land side of the levee. 75

In testimony whereof I have signed my name to this specification.

PERRY L. HEDRICK.
